UNITED STATES PATENT OFFICE.

HERMAN R. DORE, OF MOULTONVILLE, NEW HAMPSHIRE.

RAILROAD-SIGNAL.

SPECIFICATION forming part of Letters Patent No. 633,717, dated September 26, 1899.

Application filed June 10, 1899. Serial No. 720,068. (No model.)

To all whom it may concern:

Be it known that I, HERMAN R. DORE, a resident of Moultonville, in the county of Carroll and State of New Hampshire, have invented certain new and useful Improvements in Railroad-Signals; and I do hereby declare the following to be a full, clear, and exact description of the invention, such as will enable others skilled in the art to which it applies to make and use the same.

My invention relates to an improvement in railroad-signals, the object of the invention being to provide a system of block-signals which will operate automatically when a locomotive passes over the track.

A further object is to provide a system of railroad-signals which will be so constructed as to operate the semaphores at each end of a block and sound an alarm and operate a danger-signal at a road or street crossing.

A further object is to provide a railroad-signal system which will operate automatically to raise and lower the semaphores at the respective ends of a block simultaneously when a train is entering or leaving a block.

With these objects in view the invention consists in certain novel features of construction and combinations and arrangements of parts, as will be more fully hereinafter described, and pointed out in the claims.

In the accompanying drawings, Figure 1 is a plan view showing an application of my improvements to a railroad. Fig. 2 is an elevation, partly in section, of the same. Fig. 3 is an enlarged detail view in side elevation, illustrating two semaphores and co-operating devices. Fig. 4 is a rear view of a post and semaphore devices, and Fig. 5 is a plan view showing the alarm mechanism.

A represents a railroad-track, and B a series of posts arranged one at each end of a block of any desired length. Vertically-disposed rods 1 are mounted to turn in suitable bearings on each post B and are provided on their upper ends with arms 2, secured between their ends on the upper end of the rods and provided with a hole or opening in each end for a purpose more fully hereinafter explained.

The lower end of each rod 1 is made with a horizontal arm 3, provided at its free end with an inverted-U-shaped yoke 4, between

the vertical members of which a crank-arm 5, at one end of a rock-shaft 6, is disposed. The rock-shaft is mounted in suitable bearings 7 and terminates between the rails of the track, being provided at its free outer end with an upwardly-projecting arm 8 to be struck by a locomotive for the purpose of rocking the shaft to operate the semaphores, and said shaft is normally retained in such position as to maintain the arm 8 in a vertical position by means of springs 9. Each spring 9 is secured between its ends to a pin on the rock-shaft and is coiled around the shaft and secured at its end to a timber or box 10.

Each arm 2 is provided near one end with a hole 11, in which one arm of a bell-crank lever 12, pivoted to the post, as shown at 13, is secured, and the other end of the bell-crank lever is connected to a semaphore 14, pivotally attached to the post. The arm 2 at one end of a block is connected with the arm 2 at the other end of the block by wires 15, which pass through holes in the end of the arms and extend diagonally from one end of one arm to the other end of the other arm and are supported in eyes 16 in opposite sides of poles 17, disposed at points throughout the block.

One end of each wire is partially coiled, as shown at 18, to take up the necessary contraction and expansion of the wires due to the change of temperature.

C represents a crossing, and D a post disposed in proximity thereto. An electric bell 19 is secured to one side of the post D, and an arm 20 is pivoted between its ends on the upper end of the post and is provided with an outwardly-projecting contact-point 21, adapted to make contact with a block 22, pivoted to the top of the post. One of the wires 15, connected with the semaphore devices, is provided between its ends with a bar 23, cut out on its upper edge to form a recess for the reception of one end of the arm 20, which is provided with a covering 24 of insulating material, and said bar 23 is provided with a projection or shoulder 25 to strike the end of the arm and move the same when the wire 15 is moved in one direction. The other end of the arm 20 is provided with an outwardly-projecting lug 26, adapted to be engaged by one

member of a bell-crank lever 27. The other member of the bell-crank lever is connected with a crank-arm on one end of a rock-shaft 28 (similar to the rock-shafts 6) by a rod or pitman 29. The block 22 is provided on one side with a lug or projection 30, disposed in a hole or opening in the bar 23. Any suitable electric battery 32 may be employed to operate the electric bell and in the circuit of which 5 battery the circuit-breaker, comprising the arm 20 and block 22, is included. The operation of this portion of my invention is as follows: When a rock-shaft 5 at one end of the block including the crossing C is struck by a 10 locomotive, it will (simultaneously with the operating of the semaphores at each end of the block) pull the block 22 to a position to throw the contacts together and sound the alarm. The bell will ring until the locomotive 15 strikes the rock-shaft 28, which will operate the bell-crank lever 27 to throw the arm 20 out of engagement with the block 22, and hence break the circuit and stop the sounding of the bell. When the locomotive strikes 20 the rock-shaft 5 at the other end of the block, it will pull the bar 23, and the shoulder 25 thereon will strike the insulated arm 20 and throw the same to its first position, ready to be again operated to sound the alarm.

25 30 A crossing-signal 33 is pivoted to the post D and comprises two parallel strips 34, having a colored transparent portion 35 (preferably of glass) near their forward ends and connected together by a strip 36. The lower portion of one strip 34 is connected with one of the wires 15, so that when a train is entering 35 the block it will operate the wire to pull the crossing-signal 33 to a vertical position and show the danger-signal and when the train 40 leaves the block it will throw the crossing-signal to a horizontal position and hide the colored portion thereon behind a suitable screen 37 provided for the purpose.

45 Various slight changes might be resorted to in the general form and arrangement of the several parts described without departing from the spirit and scope of my invention, and hence I would have it understood that I do not wish to limit myself to the precise details 50 set forth, but consider myself at liberty to make such slight changes and alterations as fairly fall within the spirit and scope of my invention.

Having fully described my invention, what 55 I claim as new, and desire to secure by Letters Patent, is—

1. In a danger-signal for railroads, the combination with a post, of a semaphore pivoted to said post, a vertical rod mounted on said 60 post, a horizontal arm secured between its ends on said rod, a yoke on the other end of said rod, a bell-crank lever connecting one end of said arm with the semaphore and a rock-shaft adapted to be struck by a passing 65 locomotive to operate the yoke and semaphore.

2. In a block-signal for railroads, the com-

bination with a post at each end of the block, of a semaphore pivotally connected therewith, a vertical rod connected to each post, 70 a horizontal arm secured between its ends to each of said rods, diagonally-disposed wires connecting opposite ends of said arms, a bell-crank lever connecting each arm with its semaphore, and means in proximity to the track adapted to be struck by a passing locomotive to operate the rods, to raise and lower the semaphore.

3. In a railroad-signal, the combination with a post disposed at each end of a block, 80 of a semaphore pivotally connected to each post, two vertical rods connected with each post, arms secured between their ends on each rod, diagonally-disposed wires secured at opposite ends of said arms at respective ends of 85 a block, a yoke secured to each of said rods, rock-shafts in proximity to the track and having an end disposed in and adapted to move in said yokes and bell-crank levers connecting the arms and semaphores so that 90 when the yokes are operated by the rock-shafts the arms at each end of a block will raise or lower the semaphores simultaneously.

4. In a railroad-signal, the combination with posts disposed at the respective ends of 95 a block, of vertical rods connected with said posts, arms on said vertical rods, diagonal wires secured at opposite ends of said arms at the respective ends of a block, an electric alarm, a circuit-closer in the circuit of said 100 electric alarm, and means for operating said circuit-closer.

5. In a railroad-signal, the combination with posts disposed at respective ends of a block, of a post disposed between said first-mentioned posts, an electric alarm, a circuit-closer and visible signal on said central post, operating means on said first-mentioned posts adapted to be operated by a train, and connecting devices between the train-operated devices and the visible signal and circuit-closer.

6. In a railroad-signal, the combination with posts disposed at respective ends of a block, of a vertical rod connected to each of 115 said posts, an arm secured between its ends on the upper end of said rod, an outwardly-projecting member on the lower end of each of said rods, a vertically-disposed inverted-U-shaped yoke secured on the outer end of said member, a rock-shaft having one end disposed in said yoke and the other in proximity to the track and adapted to be struck by a locomotive, diagonal wires connecting 125 opposite ends of the arms so as to operate them simultaneously, and means connected to said arms for operating a semaphore on each post when a rock-shaft is struck by a locomotive.

7. In a railroad-signal, the combination 130 with two posts and a semaphore mounted on each post, of a vertical rock-shaft having a horizontal arm at its lower end, a yoke depending from said horizontal arm, a horizon-

tal rock-shaft adapted to be actuated by a train, a crank-arm on said horizontal rock-shaft normally disposed between the ends of said yoke, a connection between each vertical shaft and the respective semaphore and means for communicating motion from one vertical rock-shaft to another.

In testimony whereof I have signed this specification in the presence of two subscribing witnesses.

HERMAN R. DORE.
